[57] CLAIM

The ornamental design for a kitchen faucet, as shown and described.

DESCRIPTION

FIG. 1 is front perspective view of a kitchen faucet showing our new design;

FIG. 2 is a rear perspective view thereof;

FIG. 3 is a top plan view thereof;

FIG. 4 is a front elevational view thereof;

FIG. 5 is a right side elevational view thereof, the left side being a mirror image;

FIG. 6 is a rear elevational view thereof; and,

FIG. 7 is a bottom plan view thereof.

The broken line showing of the escutcheon in FIGS. 1-7 is for the purpose of illustration only and forms no part of the claimed design.
